UNITED STATES PATENT OFFICE

THOMAS J. VIVIANO, OF CARNEGIE, PENNSYLVANIA

DESIGN FOR A MERCHANTISE-DISPLAY RECEPTACLE

Application filed April 19, 1929. Serial No. 30,937. Term of patent 14 years.

To all whom it may concern:

Be it known that I, THOMAS J. VIVIANO, a citizen of the United States, residing at Carnegie, in the county of Allegheny, State of Pennsylvania, have invented a new, original, and ornamental Design for Merchandise-Display Receptacles, of which the following is a specification, reference being had to the accompanying drawing, forming part thereof.

The figure is a perspective view of a merchandise display receptacle, showing my new design.

I claim:

The ornamental design for a merchandise display receptacle, as shown.

In testimony whereof I affix my signature.

THOMAS J. VIVIANO.
